HARRY H. HELLAWELL, OF FAIR LAWN, AND FERDINAND RADHUBER, OF UNION CITY, NEW JERSEY, ASSIGNEES TO THE SCHWARZENBACH-HUBER COMPANY, OF UNION CITY, NEW JERSEY, A CORPORATION OF NEW JERSEY.

CUSHION FOR CREELS OR JACKS.

Application filed April 11, 1927. Serial No. 182,872.

This invention relates to creels or jacks, and has for an object to provide an improved construction wherein a yielding action is provided so that undesirable strains on the yarn will be eliminated.

Another object of the invention is to provide a creel or jack wherein a pivotally mounted structure is presented, designed to yield after a given pull.

10 A still further object, more specifically, is to provide a pivotally mounted creel or jack with adjustable resilient means normally holding the jack in a given position and permitting a limited pivotal or swinging movement of the creel.

In the accompanying drawings—

Figure 1 is a front view of a creel disclosing an embodiment of the invention, certain parts being broken away in order that the 20 creel may be shown on an enlarged scale.

Figure 2 is a sectional view through Figure 1 on line 2—2.

Figure 3 is a view similar to the lower 25 part of Figure 2 but showing the parts on an enlarged scale.

Figure 4 is a detail fragmentary elevation of the lever, guide and associated parts shown in Figure 3 and embodying certain features of the invention.

30 Figure 5 is a sectional view through Figure 3 on line 5—5.

Referring to the accompanying drawings by numerals, 1 indicates broadly the creel or jack and 2 the pivotal mechanism for permitting the creel 1 to swing within certain limits. The creel 1 is provided with the usual frame 3 having the usual pins 4 for receiving the spools. A roller 5 is arranged at the top of frame 3, said roller guiding the yarn as it passes between the various pins 6. At the bottom of the creel a number of supporting rollers 7 are provided. The parts from 3 to 7 inclusive, are old and well known and, therefore, will need no additional description.

45 Heretofore, there were usually four rollers 7 arranged near the four corners of the creel whereby the creel could be moved as desired. When first starting a loom there is a considerable tension on the yarn before the spools on pin 4 begin to rotate properly and the other parts begin to move properly. Oftentimes some of the yarn breaks during the starting operation, and when this occurs,

the entire machine must be stopped and the 55 break repaired. In the present invention, the creel has been provided with means for permitting a yielding or swinging action of the creel toward the loom after a certain tension has been brought to bear on the yarn 60 and in this way the tension is relieved while the parts are adjusting themselves to the weaving operation.

In order to bring about this result, the 65 wheels 7 are left in place on the side of the frame 3 which faces the loom. The wheels on the opposite side are removed and auxiliary wheels 8 are provided which ordinarily act the same as the wheels 7, namely, to assist in supporting the creel so that it may be 70 wheeled from place to place. Preferably there is one wheel 8 near each end of the creel, though others could be provided and other mechanism 2 could be provided and associated with the respective wheels 8. As 75 the structure 2 and the wheels 8 are all identical, the description of one will apply to all, whether there is one, two or more used.

As indicated particularly in Figures 3 and 80 5, the wheel 8 is journaled on a rounded extension 9 of the bar 10. This bar is bolted or otherwise secured to the frame 3 by a suitable bolt 11 extending through the bar near the front end 12. The end of bar 10 nearest the wheel 8, loosely extends through a forked member 13 which is secured to the frame 3 by screws or otherwise, said forked member acting as a guide for the bar 10. A lever 14 is provided, bent at 15 so as to provide an extension 16. A bolt 17 loosely 90 extends through bar 10 and through lever 14 at the bend 15, a washer or other spacing member 18 being placed between bar 10 and lever 14. As the opening through which the bolt 17 passes is larger than the bolt, the connection is sufficiently loose to allow the lever 14 to swing pivotally to an appreciable extent. The extension 16 projects through the opening 19 in the forked member 13 and bears against the bottom beam 20 of the 95 frame 3. A retractile spring 21 has one end secured to the bar 10 and the other end connected to a bolt 22 which extends through a suitable opening in lever 14 and which accommodates the wing nut 23. By adjusting 100 the wing nut 23, the effective action of spring 21 may be varied.

As illustrated in the drawing, the spring 105

As illustrated in the drawing, the spring

21 is completely contracted but is reasonably taut so that it will begin to act immediately upon the swinging movement of the frame to the left as shown in Figure 2. As the frame swings from the top toward the left in Figure 2, it will force the extension 16 downwardly and, consequently, will pull on the end of spring 21 which will resist more or less this pulling action. In case there is a long heavy pull, the frame 3 will swing until the extension 16 is resting on the bar 10. This will be the limit of the swinging action but usually the frame does not swing to this extent. After the parts have begun to operate, the tension will automatically decrease as the spools on the pins 14 have begun to revolve and the other parts begun to move. When the inertia of these parts has been thus overcome, all parts will operate in a smooth and efficient manner and the frame 3 will gradually move back into substantially the position shown in Figures 2 and 3. In case there should be a breakage of any of the yarn at any time, and the machine stopped, the same action will take place, namely, the creel will yield as the machine is again started.

What we claim is:

1. A creel including a frame and supporting wheels along one side, a plurality of bars connected to said side and extending to the opposite side, a supporting wheel mounted on the free end of each of said bars, a pivotally mounted lever mounted on each of said bars with one end engaging the lower edge of the frame for supporting the same, and a spring acting on the opposite end of the lever for resiliently holding the lever in a given position.
2. A creel or jack including a frame having supporting members on one side, supporting wheels on the opposite side, a swinging bar connected to each of said wheels and to the frame whereby the frame on the side of the wheels may move up and down in a swinging movement, and resilient means for supporting the frame adjacent the wheels and means for resiliently resisting the downward movement of the frame at this point.
3. A creel including a frame and a plurality of supporting means, the supporting means on one side of the frame including a bar pivotally connected to said frame on one side and extending to the other side, a traction member for supporting the end of said

bar extending to said other side, a substantially L-shaped lever pivotally mounted on said bar at the juncture of the arms of the lever, said lever being positioned so that one end will extend beneath said frame above said traction member for supporting that side of the frame, and a spring member for resiliently holding the said opposite side of the frame in a given position and for allowing that side of the frame to move downwardly as the top of the frame is moved substantially horizontally whereby a swinging movement will be given the frame.

4. In a creel, a frame, a plurality of supports, the supports including wheels on one side, a bar acting as an axle for said wheels, said bar at the opposite end being connected with said frame, means carried by the frame straddling said bar, a lever pivotally mounted on said bar with one end extending through said straddling means, said end acting as an auxiliary support for that side of the frame, and an adjusted spring for normally holding said lever in a given position.

5. In a creel, a frame, a plurality of bars connected at one end to one side of the frame and extending to the opposite side across the bottom of the creel, a traction member connected to the free end of each of said bars, a forked member secured to said frame and loosely straddling each of said bars, a substantially V-shaped lever for each of said bars pivotally mounted on the respective bars at the apex of the lever, one end of the lever engaging the edge of the frame carrying the forked member for supporting a frame at that point, and a spring connected to said bar and to the free end of said lever for resiliently holding the lever in a given position.

6. A creel having rearward, underneath and forward sides and means to hold a number of freely rotative wound packages and guiding means over which the threads from said packages are to extend when they are simultaneously drawn forward with respect to the creel, said creel being forwardly and rearwardly tiltable and having rearward and forward supporting means on the rearward one of which the creel is thus tiltable and the forward one of which is arranged at the underneath side of the creel and yieldingly opposes the forward tilting of the creel.
